Primary Examiner — Joseph Kukella*Assistant Examiner* — Lavon M. Amerson(74) *Attorney, Agent, or Firm* — Daniel M. Cohn; Howard M. Cohn(57) **CLAIM**

The ornamental design for a rollator walker as shown and described.

DESCRIPTION

FIG. 1 is a perspective view of a rollator walker showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1; and, FIG. 10 is a partial enlarged view of portion 10 in FIG. 2. The broken lines depict portions of the rollator walker and form no part of the claimed design.

The unevenly dashed broken lines in FIGS. 9 and 10 illustrate the boundary of the enlarged views and form no part of the claimed design.
